UNITED STATES PATENT OFFICE

ALFRED R. WILSON, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed February 17, 1930. Serial No. 429,126.

The invention relates to car roofs of the flexible type and has more particular reference to the construction of the transverse caps which weatherproof between adjacent roofing sheets. In the present state of the art the roofing sheets are laid upon the car frame, being separated from each other by mullion strips and being weatherproofed by transverse caps. These transverse caps embrace the mullions and upstanding flanges on the sheets with sufficient clearance to permit independent movement of the sheets during the flexing and weaving of the car. The caps also press downward upon raised bearings at the margins of the sheets to form a thoroughly weatherproof joint and also to hold the sheets from vertical displacement. It is, however, necessary to hold down the caps and it has been the practice heretofore to accomplish this by bolts depending from the caps and secured to apertured brackets which are mounted on the side plate of the car frame or to the facia thereof. Thus in assembling the roof after the sheets are laid between the mullions on the roof frame, the transverse caps are placed in position, being secured by the bolts to the apertured brackets either prior or subsequent to the securing of the latter to the car frame.

A serious defect in the construction as above given is that the apertured brackets are not accurately located with respect to the transverse caps and car frame so that the caps are not properly positioned. This necessitates work on the field for correcting the error which greatly increases the cost of erection. Furthermore, where as in some constructions, the bolts are secured to the apertured brackets inside of the car body, the operator is not in a position to observe whether he is properly positioning the caps with reference to the sheets or tightly clamping them down upon the sheets.

To avoid this objection I have devised a construction in which the holding down means for the transverse caps is entirely external to the car body and is so located as to avoid any danger of misplacement. Preferably I accomplish this by passing the holding down bolts through vertical apertures in the

facia thereby not only securely drawing down the caps on the sheets but also accomplishing this at the eaves where the workman can observe what he is doing. This construction is shown in the accompanying drawing in which:

Figure 1 is a section through the side plate, facia of the car frame and through one of the transverse caps in the central plane thereof;

Figure 2 is a plan view;

Figure 3 is an end elevation, and

Figure 4 is a cross section through the transverse cap on line 4-4 of Figure 2.

As illustrated, A is the side plate of the car frame; B the mullion strip; C the sheathing or outer side wall of the car, and D the filler block at the upper end of the sheathing and to which the facia E is secured. These parts may all be of usual construction with the exception that I preferably form the facia of something more than usual thickness and may diminish the vertical height thereof. The roofing sheets F are laid upon the car frame between the mullions B and with their upstanding flanges F' parallel to but spaced from said mullions and with inwardly extending horizontal flanges F² resting on the mullions. The sheets may have the usual downturned eaves flanges G which as shown have the return bends H for engaging flashings I secured to the facia. The transverse caps J embrace the mullions B and upstanding flanges F' and are provided with the usual laterally extending flanges J' which rest upon raised bearing portions F³ of the sheets clamping them down to the car frame and forming a weatherproof joint.

For securing the caps J in position and for drawing them down upon the sheets, said caps are provided in the portion above the facia E with a horizontal bearing J² to which is secured preferably by riveting, a shoulder bolt K. This bolt depends from the bearing J² and passes through a vertical bore in the facia E which is so located as to hold the cap J centralized with respect to the mullion B. The lower end of the bolt engages a clamping nut L which after suitable adjustment is secured by a lock washer 106.

M. This construction permits the workman assembling the roof to position the cap by first engaging the bolt K with the aperture in the fascia and then pressing the cap vertically downward. The desired clamping pressure may then be placed on the cap by screwing up the nut L and as the workman is in a position to observe the outside of the roof at the time of his making this adjustment, he may more readily accomplish the same.

The fascia E may be bored to receive the bolts K prior to its installation on the car and may then be secured by nailing or in any other suitable manner.

A further advantage of my improved construction is that by dispensing with the apertured bracket which is usually employed for engaging the depending bolt of the transverse cap I may have the upper face of the side plate A free from obstruction and thereby provide a wide bearing for supporting the eaves end of the mullions B.

What I claim as my invention is:

1. In a car roof of the flexible type, the combination with a roof frame and a plurality of roofing sheets laid thereon having downturned flanges overlapping and spaced from the eaves, of a transverse cap or weatherproofing between adjacent sheets having downturned flanges outside the flanges of said sheets and means external of the car body but inside said downturned flanges for drawing down said transverse cap upon said sheets whereby said caps and sheets are held down with freedom for relative lateral movement.

2. In a car roof of the flexible type the combination with a roof frame and a plurality of roofing sheets laid thereon having downturned flanges overlapping and spaced from the eaves, of a transverse cap for weatherproofing between said sheets having downturned flanges outside the flanges of said sheets, a bolt depending from said cap external to the car body but inside said downturned flanges and an apertured bearing secured to the side of the car for co-operating with said bolt to form a holding down means for the cap whereby said caps and sheets are held down with freedom for relative lateral movement.

3. In a car roof the combination with a roofing frame and a plurality of roofing sheets laid thereon having downturned flanges overlapping and spaced from the eaves, of a transverse cap for weatherproofing between said roofing sheets having downturned flanges outside the flanges of said sheets, a bolt depending from said transverse cap external to the car but inside said downturned flanges, and a fascia apertured to receive said bolt and co-operating therewith to form a holding down means for said cap whereby said caps and sheets are held down

with freedom for relative lateral movement.

4. In a car roof, the combination with a skeleton roof frame, of a mullion extending transversely of said frame, roofing sheets laid upon said frame upon opposite sides of said mullion, said sheets having upturned side flanges and lateral extensions for resting upon said mullion and also having downturned flanges overlapping and spaced from the eaves, a transverse cap for embracing said mullion and upstanding flanges on said sheets and having downturned flanges outside the flanges of said sheets, a bolt secured to said transverse cap in a portion thereof external to the car body and depending vertically therefrom, a fascia apertured to receive said bolt and a clamping nut engaging said bolt below said fascia forming a drawing down means for said cap whereby said caps and sheets are held down with freedom for relative lateral movement.

5. In a car roof the combination with a roof frame and a series of roofing sheets laid thereon, of a fascia vertically apertured in positions intermediate adjacent sheets, transverse caps for weatherproofing between adjacent sheets, each cap having a portion extending downward outside said fascia and a horizontal portion above said fascia, a bolt secured to said horizontal portion and depending therefrom, said bolt passing through the aperture in the fascia, a nut engaging the lower end of said bolt beneath said fascia forming a drawing down means for the cap upon the sheets and means for locking said nut from disengagement whereby said caps and sheets are held down with freedom for relative lateral movement.

In testimony whereof I affix my signature.

ALFRED R. WILSON.
